A. G. Burns

ATTORNEY

UNITED STATES PATENT OFFICE.

CHARLES L. RUSE, OF WARSAW, INDIANA, ASSIGNOR OF ONE-HALF TO GEORGE J. STEINMETZ, OF PERU, INDIANA.

RAILWAY-RAIL BRACE.

Application filed February 1, 1927. Serial No. 165,124.

This invention relates to improvements in railway rail braces, and the object thereof is to provide an easily applied connection between the rails of a railway by which the 5 rails are maintained in fixed spaced relation with each other without forming an obstruction to the rolling stock moving upon the railway. It frequently occurs when braces of the ordinary construction are employed, 10 that the braces become broken or buckled because of contact with displaced members of the rolling stock, and the rails thereby become loosened from their anchorage and tend to spread apart with consequent liability of 15 derailment of the car wheels, and therefore, the present invention contemplates the elimination of such liability.

The object of the invention is accomplished 20 by the construction illustrated in the accompanying drawings, in which:

Fig. 1 is an elevation showing a brace embodying the invention applied to a pair of railway rails; and

Fig. 2 is a plan view projected from Fig. 1. 25 The characters appearing in the description refer to parts shown in the drawings and designated thereon by corresponding characters.

The invention consists of a pair of brace 30 members 1 and 2, the one being the counterpart of the other and positioned oppositely. The adjacent ends of said members are bent at right angles to form corresponding feet 3 which are connected together by a bolt 4 that 35 extends through said feet and through a sleeve 5 that is positioned between said feet so that the said brace members are held spaced apart a fixed distance. The bolt has a nut 6 on its extending end, which when 40 tightened, causes the sleeve 5 to be clamped between the feet 3 of said members, and a cotter pin 7 extends through the projecting end of the bolt to prevent retraction of the nut.

45 Each brace member is made out of a flat bar twisted in its middle portion so that its inner end extends vertically edgewise while its outer end lies flat horizontally. At the outer end of each member is formed a hook

8 shaped to receive the outer flange 9 of the 50 corresponding rail 10, and a dog 11 is secured by a bolt 12 to each brace member at a point thereon spaced from its hooked end so that the jaw 13 of the dog will be clamped upon the inner flange 14 of the corresponding 55 rail. Each bolt 12 is provided with a cotter-pin 15 to prevent the nut 16 thereon from retracting.

In utilizing the invention the brace members are placed in position opposite each 60 other with their respective outer ends hooked onto the outer flanges of the corresponding rails, and the dogs 11 are secured in position on said members so that the inner flanges of the corresponding rails are 65 clamped thereby upon said members. The sleeve 5 is then positioned between the feet of said members, and the connecting bolt 4 is applied through said feet and sleeve. The nut 6 is then tightened so that the feet of 70 said members are drawn firmly against the corresponding ends of the sleeve. When the invention is thus applied the rails are held a fixed distance apart, and the gauge of the 75 railway track is thereby established and maintained.

What I claim is:—

1. A railway rail brace consisting of a pair of oppositely disposed brace members, each comprising a flat bar twisted in its middle portion so that one of its end portions extends edgewise in a vertical plane while its opposite end extends edgewise horizontally, one end of each member having a hook engageable with the outer flange of one of the 80 rails of a railway track, its opposite end having a foot formed thereon; a spacing member positioned between the feet of said brace members; a bolt extending through said feet and brace members to establish and 85 maintain said members a fixed distance apart; and a dog on each brace member in clamped engagement with the inner flange 90 of the corresponding rail.

2. A railway rail brace consisting of a 95 pair of oppositely disposed brace members, the outer end of each member extending beneath the corresponding rail of said railway

and having a hook engageable with the outer flange thereof, the opposite end of said brace member having a foot formed thereon; a spacing member positioned between said members with its ends bearing correspondingly against the feet thereof; a bolt extending through said feet and securing said spacing member in clamped relation with said feet; and a clamping means on each brace member engaging the inner flange of the corresponding rail.

In testimony whereof I affix my signature.

CHARLES L. RUSE.
